UNITED STATES PATENT OFFICE

1,964,677

AUTOGRAPHIC REGISTER

Bernard A. Schroeder, Evanston, Ill., assignor to
 United Autographic Register Co., Chicago, Ill., a
 corporation of Illinois

Application March 31, 1933, Serial No. 663,773

19 Claims. (Cl. 282—16)

This invention relates particularly to autographic registers of the hand pull-out type having a filing compartment to receive a record strip.

The primary object of the present invention is to provide a machine in which stationary strips, provided with marginal perforations, are kept in register by pin-wheels and upon the manual withdrawal of an issuing strip a record strip is propelled into the record compartment by the action of the pin-wheels. Machines of this character are generally provided with a tear-off bar and it is a further object of this invention to provide means for initially advancing the ends of the strips from beneath said bar so that they may readily be grasped by hand. Another object is to provide a measured feed for the stationery and this is accomplished by providing stop means which permit but one revolution of the pin-wheels at a time.

The invention is illustrated in a preferred embodiment in the accompanying drawings, in which—

Fig. 1 is a broken side elevational view of the machine partly in section taken as indicated at line 1 of Fig. 4; Fig. 2, an enlarged vertical sectional view taken as indicated at line 2 of Fig. 4; Fig. 3, a sectional view taken as indicated at line 3—3 of Fig. 1; Fig. 4, a broken plan view of the machine; Fig. 5, a broken longitudinal sectional view showing a modified form of initial feed device; Fig. 6, a broken longitudinal sectional view of a modified form of pin wheel adapted to form its own perforations in the stationery; Fig. 7, a broken longitudinal sectional view showing another form of initial feed device; and Fig. 8, a view similar to Fig. 7, showing the device in locked position.

In the preferred embodiment illustrated in Figs. 1—4, A designates a casing or frame provided with a packet-holding compartment A', a record compartment A², a platen A³ forming a closure for the compartment A', a skeleton cover A⁴ adapted to partially enclose the platen, and a cover member A⁵ forming a top for the compartment A²; B, an initial feed device adapted to initially advance the stationery over the platen by moving the pin-wheels; C, the pin-wheel mechanism for holding the strips in constant alinement; and D, a carbon strip roll container over which carbon strips may be led across the platen A³.

The casing A may be of any suitable construction, and preferably the platen is pivotally connected at one lateral edge of the casing, in the well known manner, and the skeleton cover A⁴

may be pivoted at the rear end of the casing A so that the latter may be swung rearwardly to give access to the platen when it is desired to load the machine. The skeleton cover is shown provided at its front end with an integrally formed tear-off bar 10 which is adapted to overlie the aligning mechanism and facilitate the severing of an issued form.

The cover A⁵ is pivoted at 11 to the upper front portion of the casing of the machine. The cover is provided at its rear end with a hingedly connected separator member 12 the point of which is adapted to be inserted beneath the tear-off bar 10 and separate the issuing strip from the record strip. A hinge 13, between the separator and cover members may also form a pivotal support for a downwardly extending deflector plate 14 which serves to direct re-folding of the stationery strips within the compartment A². The cover may also be provided with a lock 15 to prevent unauthorized access to the filing compartment.

The initial feed device B comprises an upwardly extending arm 16 which is provided at its upper end portion with a knob 16^a which is capable of limited forward and rearward movement through slots 17 and 18 in the platen and skeleton cover, respectively. A cross shaft 20 is journaled in the side walls of the machine and supports a pair of rigidly connected pin-wheels 21 and 22. The pin-wheel 21 is shown provided with an internal ratchet 21^a which is adapted to be engaged by a pawl 16^b carried by the arm 16, the latter being pivotally mounted on the shaft 20. The wheel 21 is further provided with a stop 23 which is engaged by a locking arm 24 pivotally connected to the arm 16 at 24^a. The locking arm is provided with a slot 24^b which is engaged by a pin 25 rigidly connected to the side wall of the machine. If desired, another pin 26 may be provided on the side wall of the machine to prevent the locking arm from being bent when it is struck by the stop 23. The slot 24^b may also serve to limit the forward and rearward swing of the arm 16. A tension spring 27, connected between the pin 28 on the wall of the machine and the arm 16 urges the latter to its rearmost position so that the locking bar 24 will be in the path of the stop 23. A small amount of lost motion is provided between the pawl 16^b and the ratchet so that when the operating arm is thrown forwardly the locking device will be released before the pawl 16^b starts rotation of the pin-wheels. If desired, an additional pawl 29 may be provided to prevent any rearward movement of the ratchet wheel due to the lost motion mentioned above.

It will be understood that in the operation of the device, the operating arm 16 is swung forwardly to release the locking device and feed the end of the upper stationery strip sufficiently beyond the tear-off bar 10 to permit the operator to grasp the same. The separator 12 is provided with guide members 12^a to facilitate grasping the end of the issuing strip and as this strip is withdrawn from the machine it will cause the pin-wheels 21 and 22 to rotate and feed a record strip into the compartment A² until the stop 23 engages the locking bar 24. A stripper member 31 is pivotally mounted in the compartment A² and serves to strip the record copy from engagement with the register pins.

The modification shown in Fig. 5 employs the same principle of operation, but in this case initial feed of the pin-wheel 35 which is mounted on the cross shaft 36, is accomplished by means of a depressible plunger 37 equipped with a cam-arm 38 which is adapted to engage a stud 35^a on the pin-wheel and cause partial rotation of the same. The plunger is further provided with a stop 39 in the path of a tooth 35^b on the pin-wheel. The plunger extends through an opening 40 in a tear-off bar 41 and its lower end is bifurcated so as to straddle the shaft 36 and be held in a vertical position. A spring 43 urges the plunger to its uppermost position where it may prevent the pin-wheel from making more than one complete revolution. It will be understood that this device is operated by depressing the plunger 37 which unlocks the pin-wheel and causes a partial rotation of the same to advance the stationery to a position where it may be grasped by hand.

In the modification shown in Fig. 6 the pin-wheels 45 are provided with prick pins 45^a which are adapted to perforate the stationery 46 which is drawn over the platen into engagement with said pins. With this form of device a forming wheel 47 may be provided over the pin wheel 45 so as to press the stationery into engagement with the pins. Obviously, this form of pin-wheel may be employed with either of the initial feed devices described above.

In the modification illustrated in Figs. 7 and 8 an initial feed device is provided which is adapted to exert a braking action on a pin-wheel as the wheel approaches the end of one complete revolution. This energy is stored up in a tension spring and upon release of a cam-arm or latching device the energy is used to initiate rotation of the wheel automatically.

55 A pin wheel 50 provided with a roller 51, is fixedly mounted on a shaft 52 which is journaled in the side walls of the casing 53. A cam-arm 54 is pivotally connected to the casing at 54^a and is provided at the opposite end with a spring 55 which urges the cam-arm into engagement with the roller 51. The cam-arm is provided with a notch 54^b which is adapted to engage the roller to prevent rotation of the wheel when in the position shown in Fig. 8. In order to release the wheel a finger-operated bellcrank 56 is pivotally mounted at 57 on the cam-arm 54, and is provided with a curved lower end portion 56^a which is adapted to bear against the roller and release the wheel by raising the arm 54. The curvature in the arm 56^a enables the member to exert a slight driving action on the roller 51 and this slight movement assists the cam arm in causing a partial rotation of the pin wheel and loosening the stationery strips 58 from engagement with the interleaved carbon (not shown). A

small tension spring 59 urges the arm 56^a into its uppermost position against a stop 54^c on the arm 54. In this form of feed device the pin wheel is caused to rotate by the operator withdrawing a strip 58 from above a cover member 60. As one of the forms reaches the end of its travel the roller 51 engages the cam-arm 54 and raises it into latching position. The operator may then sever the issued strip on a tear-off bar 61. After the next set of forms has been filled in the operator swings the finger-member 56 rearwardly to release the wheel and automatically initiates partial feed of the next set of forms so that their ends may be grasped beyond the tear-off bar. If for any reason the spring 55 is not able to partially rotate the wheel its action may be augmented by the operator pressing downwardly on the member 56, but ordinarily this action is not needed.

The foregoing detailed description is given for clearness of understanding only and no unnecessary limitations should be understood therefrom but the appended claims should be construed as broadly as permissible in view of the prior art.

What I regard as new, and desire to secure by Letters Patent, is:

1. In a register: a casing provided with a platen over which a plurality of superposed continuous-form stationery strips may be led, a record compartment adapted to receive and store one of said strips, and a tear-off bar for severing an issuing strip; a wheel having pins adapted to engage the strips and hold the same in register so that manual withdrawal of the issuing-strip will propel a record strip into the record-compartment; and an initial feed-device having a measured feed of less than a form-length for advancing the ends of the strips, under said tear-off bar.

2. Mechanism as specified in claim 1, in which means are provided for automatically arresting the advance of strips after a form-length has been withdrawn.

3. Mechanism as specified in claim 1, in which locking means are provided for automatically arresting the advance of strips after a form-length has been withdrawn and means are provided on said initial feed-device for releasing the locking means.

4. In a device of the character set forth: a platen over which continuous-form stationery provided with marginal perforations may be led; a pin-wheel adapted to engage the perforations in said stationery, the circumference of said wheel being equal to one form-length of the stationery; a measured stroke device for partially rotating said wheel; and means for automatically stopping said wheel after one complete revolution thereof.

5. Mechanism as specified in claim 4, in which the platen is provided with a slot and the measured-stroke device comprises a pivotally mounted arm extending through said slot and adapted to engage the pin-wheel.

6. In a device of the character set forth: a casing having a platen over which continuous-form stationery provided with marginal perforations may be led; a ratchet-wheel journaled in said casing and having pins adapted to engage the perforations and advance the stationery; an initial feed device comprising a lever-arm having a limited forward and rearward stroke, said arm having a pawl adapted to engage the teeth of said ratchet-wheel and partially rotate the wheel; and a second pawl pivotally mounted on said cas-

- ing so as to engage the same teeth and prevent reverse rotation of said wheel.
7. Mechanism as specified in claim 6, in which the arm is equipped with a locking device adapted to lock the wheel after each complete revolution, and means for automatically releasing the same during the forward movement of said arm.
8. In a device of the character set forth: a casing having a platen over which continuous-form stationery provided with marginal perforations may be led; a ratchet wheel journaled in said casing and having pins adapted to engage the perforations and advance the stationery; a lever-arm having a limited forward and rearward stroke and provided with a pawl adapted to engage said ratchet-wheel and partially rotate the same; a locking arm carried by said lever-arm and adapted to lock said ratchet-wheel after each complete revolution; a spring urging said lever-arm to locking position; and a pawl adapted to prevent rearward movement of the ratchet-wheel.
9. In a device of the character set forth: a platen over which continuous-form stationery having marginal perforations may be led; a pin-wheel journaled in said casing and adapted to engage the stationery and advance the same; and spring-held plunger means having a stop adapted to engage said wheel and prevent forward rotation thereof, and said plunger means being adapted to engage and partially rotate said wheel after the stop has been moved from engagement therewith.
10. In a device of the character set forth: a platen over which continuous-form stationery having marginal perforations may be led; a pin-wheel journaled in said casing and adapted to engage the stationery and advance the same; and means for locking said pin wheel and for partially rotating said wheel automatically upon release of the same.
11. Mechanism as specified in claim 10, in which the means comprises a spring-held cam-arm for engaging said wheel, said cam-arm exerting a driving action during one portion of the rotation of the wheel and a braking action during another portion of said rotation.
12. In a device of the character set forth: a platen over which continuous-form stationery having marginal perforations may be led; a pin wheel journaled in said casing and adapted to engage the stationery and advance the same, said pin wheel being equipped with a stud; a cam-arm adapted to engage said stud and drive the wheel, said cam-arm having a notch adapted to engage a stud and lock the wheel; and finger-operated means for releasing the stud from engagement with said notch.
13. Mechanism as specified in claim 12, in which the finger-operated means comprises a bell-crank member pivotally mounted on the cam-arm serving to raise the cam-arm notch from engagement with the stud and to exert a turning action on the wheel.
14. In an autographic register: a casing having a platen over which a plurality of stationery-strips may be led; feed-means for feeding a measured length of said stationery-strips over said platen; and means for exerting a driving action on said feed-means at the commencement of a feeding movement and a braking action towards the completion of said movement.
15. Mechanism as specified in claim 14, in which the means for exerting a driving action on the feed-means comprises a spring held cam-arm engaging a stud on the feed-means.
16. Mechanism as specified in claim 14, in which the means for exerting a driving action on the feed-means also locks the feed-means at the completion of a feeding movement.
17. In an autographic register: a casing having a platen over which stationery-strips may be led; feed-means for advancing a measured length of said stationery-strips over the platen; and means for storing up energy and exerting a braking action on the feed-means near the completion of an advancing movement and for releasing energy to exert a driving action on the feed-means at the beginning of said movement.
18. In a hand pull-out autographic register: a casing having a platen over which a plurality of stationery-strips may be drawn; means for regulating the length of stationery-strips withdrawn from the register in one operation; and means for facilitating the manual withdrawal at the beginning of the movement and for gradually retarding the withdrawal near the completion of said movement.
19. In a device of the character set forth: a casing having a platen over which continuous-form stationery provided with marginal perforations may be led; a ratchet wheel journaled in said casing and having pins adapted to engage the perforations and advance the stationery; an initial feed device comprising a lever-arm having a limited forward and rearward stroke, said arm having a pawl adapted to engage the ratchet wheel and partially rotate the same; and a locking device on said arm for locking the wheel after a complete revolution, and means for automatically releasing the same during the forward movement of said arm.

BERNARD A. SCHROEDER. 130
